Harley Stone

UNITED STATES PATENT OFFICE.

HARLEY STONE, OF BLACKSTONE, MASSACHUSETTS, ASSIGNOR TO PAUL P. TODD, OF SAME PLACE.

EXPANDING BIT.

Specification of Letters Patent No. 22,474, dated December 28, 1858.

To all whom it may concern:

Be it known that I, HARLEY STONE, of Blackstone, in the county of Worcester and State of Massachusetts, have invented a new 5 and useful Improvement on Dilating Bits or Augers; and I do hereby declare that the following is a full, clear, and exact description of the construction and operation of the same, reference being had to the annexed 10 drawings, making a part of this specification, in which—

Figure 1, is a perspective view of the bit as a whole; Fig. 2, of the main bit; Fig. 3, of the bit as spread; Fig. 4, of the slide 15 cutter; Fig. 5, of the bolt which fastens the parts together.

The nature and construction of my invention consists of a bit —Fig. 1, A— with one lip —a— into which is dovetailed a 20 slide cutter —B— in which is a diagonal slit —C—. Opposite to this, and in the main bit, is another slit —Fig. 2, D— of equal length, near to, and running parallel with, the edge of the main bit. Through 25 the two slits is passed a small sliding bolt

—Fig. 5, E— having upon one end a nut —e— and upon the other a round flat head, both of which project over the edges of the slits. Stamped upon the main bit and slide cutter is a graduated scale —F— by 30 means of which the exact size can be determined.

The operation is—to loosen the nut —e— and crowd the bolt —E— toward the gimlet of the bit, till it is spread to the required 35 size as indicated by the graduated scale, and vice versa.

I claim—

The mode and application of the slide cutter —B— the slits —C— and D— the 40 bolt —E— and the graduated scale —F— and constructed and operating as above set forth and described.

In testimony whereof I have hereunto set my hand in the presence of two witnesses. 45

HARLEY STONE.
